UNITED STATES PATENT OFFICE.

CHARLES E. MACBETH AND FREDERICK C. STIENING, OF HAMILTON, OHIO, ASSIGNEES
TO THE LONG & ALLSTATTER COMPANY, OF HAMILTON, OHIO.

PUNCHING AND SHEARING MACHINE.

1,164,656.

Specification of Letters Patent. Patented Dec. 21, 1915.

Application filed August 27, 1915. Serial No. 47,582.

To all whom it may concern:

Be it known that we, CHARLES E. MACBETH and FREDERICK C. STIENING, citizens of the United States, residing at Hamilton, Butler county, Ohio, have invented certain new and useful Improvements in Punching and Shearing Machines, of which the following is a specification.

This invention pertains to machines designed for the punching of holes in metallic plates and for the transverse shearing of plates either before or after punching has been done.

Our invention will be readily understood from the following description taken in connection with the accompanying drawings in which:—

Figure 1 is a front elevation of a punching and shearing machine exemplifying our invention, portions being broken away and a portion appearing in vertical longitudinal section in the plane of line *a* of Figs. 3 and 5: Fig. 2 a rear elevation of the shear-gag: Fig. 3 an elevation of the left side of the general main parts of the machine, the bridgetree appearing in vertical section in the plane of line *b* of Figs. 1, 2, 6, and 7, and a punch-holder appearing in section in the same plane: Fig. 4 a plan of a punch-holder: Fig. 5 an elevation of the righthand side of the machine with the righthand housing omitted, the bridgetree appearing in vertical transverse section in the plane of line *b* of Figs. 1, 2, 4, 6, 7 and 8: Fig. 6 a rear elevation of half of the shear-gate: Fig. 7 a plan of half of the shear-gate: Fig. 8 a front elevation of half of the bridgetree: Fig. 9 an end elevation of the bridgetree: Fig. 10 a horizontal section of a portion of the bridgetree in the plane of line *c* of Figs. 3, 5, 8 and 9: Fig. 11 a front elevation of the interlocking rods: and Fig. 12 a plan of the interlocking mechanism.

We have seen fit to illustrate an exemplification of our invention in the form of a multiple punching machine having two side housings for the guidance of the ends of a punch-gate above a plate or sheet passing between the housings, but our invention is equally applicable to a machine in which there is a single body or housing provided with a throat through which the plate or strip is passed.

In the drawings: 1, indicates the general

frame of the machine, consisting, in the 55 illustrated exemplification, of a pair of side housings, a base piece, and a top brace connecting the tops of the housings: 2, a die-holder secured to the base piece of the frame and supporting punch dies secured to it in 60 any appropriate number and disposition along the die-holder: 3, a cam-shaft journaled in the frame over the die-holder and adapted to be rotated in any usual or suitable manner: 4, pitmen extending downward 65 from the cams on the cam-shaft: 5, the punch-gate connected with the lower ends of the pitmen and having its ends guided in the housings of the frame: 6, punch-holders secured to the bottom of the punch-gate 70 and adjustable along the same so as to co-operate with the punch-dies in the die-holder: 7, a punch secured in each punch-holder and adapted for vertical movement therein: 8, a punch-gag mounted to slide in 75 each punch-holder and take position over the upper end of the punch in such manner that when the gag is over the punch the punch will be operative to co-operate with its punch-die, and when the gag 80 is withdrawn from over the punch the punch will be at liberty to slide upward in its holder and become inoperative for the punching operation or, in other words, gagged out of action: 9, a series of punch-gag-shafts, illustrated as four in number, journaled in the front of the punch-gate: 10, punch-gag arms secured to the punch-gag-shafts and adjustable along the shafts so as to be in line with the punch-holders with 85 90 which they are to co-operate, the lower ends of these arms being connected with appropriate ones of the punch-gags: 11, a handle on each of the punch-gag-shafts: and 12, a link connecting each of arms 10 with its appropriate punch-gag.

There may be as many of the dies and punches as desired, within the lineal capacity of the punch-gate and they may be spaced apart as desired. The arms 10 of given 100 shafts 9 may be connected with such of the punch-gags as the work calls for. When the handles 11 are in inward position then the punch gags are over the punches, as seen in Fig. 3, but, by moving one of the 105 handles 11 outward, the punch-gag connected with the shaft belonging to that handle will be withdrawn from over the

punch and the punch, instead of being operative in doing its punching work, can slide upward in its holder and thus become gagged out of action. In this manner selected ones or all of the punches may be gagged out of action by appropriate manipulation of the handles 11.

So far as the parts thus far referred to are concerned, there is nothing new. See The 19 Long & Allstatter Company's Patent No. 931781 of August 24th, 1909, for punch-gag mechanism, granted on the application of the present inventors.

Proceeding with the drawings: 13, indicates a bridgetree disposed at the rear of the punch-gate and having its ends rigidly secured to the housings of the frame: 14, a shear-gate disposed at the rear of the punch-gate, between the punch-gate and the 20 bridgetree: 15, the upper shear-blade secured to the front of the shear-gate: 16, the lower shear-blade secured to the base-piece of the frame in position to coöperate with the upper shear-blade: 17, vertical guides 25 connecting the shear-gate with the bridgetree in such manner that the shear-gate may have firm support and be capable of sliding vertically in order that it may coöperate with the lower shear-blade: 18, counterbalancing mechanism connected with the shear-gate and overbalancing it in such manner that the shear-gate will be held normally in its uppermost position: 19, rigid stops carried by the frame, being illustrated 30 as projecting forwardly from the bridgetree, to limit the upward motion of the shear-gate: and 20, a projection rearwardly and rigidly from the punch-gate over the shear-gate.

40 In the drawings the punch-gate is seen in its lowermost position, the punches having completed their punching work. When the punch-gate is in this position the projection 20 is above and free from the shear-gate, and when the punch-gate rises the shear-gate will remain in its normal upward position against stop 19, being held there by its counterbalancing mechanism. In this position of the shear-gate the upper 45 shear-blade occupies an idle position above the lower shear-blade, and sheets to be punched may be passed freely through the frame and between the upper and lower shear-blades. In this condition of the machine the punching members may operate precisely as though the parts of the shearing mechanism were not present.

Proceeding with the drawings: 21, indicates a shear-gag-block mounted to slide fore-and-aft on the projection 20 at the rear of the punch-gate and occupying a normal position to the rear of the shear-gate: 22, the guides, of a dovetailed character, connecting the shear-gag-block with projection 20 of the punch-gate: 23, rods projecting through

the punch-gate and having their rear ends secured in the shear-gag-block: 24, a shear-gag-shaft journaled in the front of the punch-gate: 25, arms secured on this shaft and having their lower ends connected with the front ends of rods 23: and 26, a hand-lever on shaft 24.

If, now, it be desired to put the shear into operation, without doing any punching, it can be done, through suitable means, by 75 pulling shear-gag-block 21 forward so as to occupy a position between the top of shear-gate 14 and the projection 20 of the punch-gate. When this has been done then the shear-blades become operative, it being understood that the punches will be gagged. The shear-gag-block 21 is pulled forward by the operation of hand-lever 26. It is our preference, having due regard for the length of stroke usually given to punch-gates, to 80 arrange that the shear-gate be normally up in such position that the shear-gag block cannot be placed in active position without first depressing the shear-gate. This preference is founded on the fact that the preferred normal high position for the shear-gate brings the upper shear-blade at such 85 level that the shear-blades are normally entirely open so as not to interfere with the operation of punching.

Proceeding with the drawings: 27, indicates lugs projecting forward of the shear-gate: 28, a vertically moving rod resting on each of these lugs: 29, a depression shaft journaled in the frame: 30, arms projecting 100 from this shaft and resting on collars on rods 28: 31, an arm fast on shaft 29: and 32, a handle for depressing arm 31.

Taking the parts as they are indicated in Figs. 3 and 5, and understanding that balancing mechanism 18 holds the shear-gate in its uppermost position, and so close to projection 20 that there is no room for the shear-gag-block over the shear-gate, if handle 32 be depressed the shear-gate will be 110 forced down a proper distance, and thereupon handle 26 may be operated to draw the shear-gag-block in over the shear-gate. When this has been done then the reciprocations of the punch-gate will operate the 115 shear-gate and cause the machine to become effective as a shearing machine. The shearing members of the machine may thus be employed in transversely shearing sheets passed through the machine between the 120 housings, either with or without regard to the punching members of the machine. The housings may be throated in the usual manner, and they are so illustrated, and this permits sheets being passed through the machine in a direction parallel with the shears so as to do slitting.

While it is manifest that our machine may do punching while the shear is inactive and that it may do shearing while the punches 130

are inactive, we consider it of high importance that provision be made for insuring that the shearing members cannot operate while the punching members are operative, and vice-versa.

Proceeding with the drawings: 33, indicates the bearings carried by the punch-gate for shear-gag-shaft 24: 34, a plate carried by the punch-gate and exemplifying an upwardly projecting surface carried by the punch-gate: 35, arms projecting rearwardly from shear-gag-shaft 24: 36, rods depending from arms 35: 37, lugs projecting rearwardly from rods 36 and adapted to engage over plate 34 so as to prevent the descent of the rods: and 38, links connecting each of the handles 11 with one of rods 36.

Assuming the parts in the relative position indicated in Fig. 3, in which the shear-gate is gagged out of action while a punch-gag is so adjusted that the punch will be effective, if it be desired to un gag the shear-gate so that the shear may become effective, it must be done by the outward movement of hand lever 26. Such outward movement of the lever will be prevented by lugs 37. Therefore, before lever 26 can be moved outwardly to make the shear effective, all of the handles 11 pertaining to the punch-gags must be pulled outwardly in order to release lugs 37 from plate 34. When all of the punch-gag handles have been moved outwardly then the shear-gag may be gotten into position to make the shear effective, and the arrangement is obviously such that this cannot be done until all of the punches are rendered ineffective. And it is also manifest that while the shear is effective no punch can be rendered effective, there thus being present an interlocking system of mechanism insuring that a punch and the shear cannot be effective at one time.

The term "gag", as used in punching and shearing machinery, calls for something in the way of definition in view of the fact that the gagging takes place when the gagging agent is out of action. By the terms "gag" or "gagging" we therefore means a device or function in which when the gag is removed from its active field the member controlled by that gag is inoperative. In other words, the gag acts by reason of its absence, to so express it.

It is to be understood that the particular constriction set forth is merely a single exemplification of our invention. We have sought to set forth the principle of our invention and the best mode in which we at present contemplate applying that principle.

We claim:—

1. A punching and shearing machine comprising in its mechanism, a frame, a die, a punch, punch-moving means connected with the punch, a punch-gag adapted to render the punch-moving means inoperative upon

the punch, a fixed shear-blade disposed near the die, a movable shear-blade adapted to be actuated by the punch-moving mechanism, a shear-gag adapted to render the punch-moving mechanism inoperative upon the movable shear-blade, and means for moving said gags, combined substantially as set forth. 70

2. A punching and shearing machine comprising in its mechanism, a frame, a die, a punch, punch-moving means connected with the punch, a punch-gag adapted to render the punch-moving means inoperative upon the punch, a fixed shear-blade disposed near the die, a movable shear-blade adapted to be actuated by the punch-moving mechanism, a shear-gag adapted to render the punch-moving mechanism inoperative upon the movable shear-blade, means for moving said gags, and interlocking means operatively connected with said gags and adapted to prevent either of the gags being moved out of gagging position while the other gag is out of active position, combined substantially as set forth. 75 80 85

3. A punching and shearing machine comprising in its mechanism, a frame, a die, a punch-gate, mechanism for moving the punch-gate, a punch movably mounted upon the punch-gate, a punch-gag associated with the punch-gate and punch and adapted to be adjusted to such position as will cause the punch-gate to impart the full measure of its stroke to the punch or to be adjusted to such position as to be ineffective of the punch, thus gagging the punch out of action, a fixed shear-blade disposed below the operative face of the die and near the die, a shear-gate, a movable shear-blade carried by the shear-gate, a projection carried by the punch-gate and extending over the shear-gate, a normally gagging shear-gag-block adapted to be interposed between said projection and the shear-gate to cause the punch-gate to become effective in moving 100 105 110 the shear-gate, and mechanism for adjusting said gags, combined substantially as set forth. 95

4. A punching and shearing machine comprising in its mechanism, a frame, a die, a punch-gate, mechanism for moving the punch-gate, a punch movably mounted upon the punch-gate a punch-gag associated with the punch-gate and punch and adapted to be adjusted to such position as will cause the punch-gate to impart the full measure of its stroke to the punch or to be adjusted to such position as to be inoperative with the punch, thus gagging the punch out of action, a fixed shear-blade disposed below the operative face of the die and near the die, a shear-gate, a movable shear-blade carried by the shear-gate, a projection carried by the punch-gate and extending over the shear-gate, a normally gagging shear-gag-block 120 125 130

adapted to be interposed between said projection and the shear-gate to cause the punch-gate to become effective in moving the shear-gate, mechanism for adjusting said 5 gags, and interlocking means operatively connected with said gags and adapted to prevent either of the gags being moved out of gagging position while the other gag is out of active position, combined substantially as set forth.

5. A punching and shearing machine comprising in its mechanism, a pair of movable gates disposed near each other, mechanism operatively connected with the gates for 15 moving them, a tool carried by each gate, and a gag for each gate to serve in throwing either selected tool out of action, combined substantially as set forth.

6. A punching and shearing machine comprising in its mechanism, a pair of movable gates disposed near each other, mechanism operatively connected with the gates for moving them, a tool carried by each gate, a gag for each gate to serve in throwing either 25 selected tool out of action, and interlocking means connected with the gags to serve in throwing either selected tool out of action, combined substantially as set forth.

7. A punching and shearing machine comprising in its mechanism, a frame, a punch-gate guided therein, a punch carried by the punch-gate, means for operating the punch-gate, a punch-gag to serve in rendering the punch inoperative while the punch is moving, a downwardly presenting projection on the rear of the punch-gate, a shear-gate disposed below said projection and guided in the frame, a gag-bar carried by said projection and adapted for movement to and from 40 a position between said projection and the shear-gate, rods projecting from the shear-gag through the punch-gate, and mechanism connected with said rods for adjusting the shear-gag to selected position, combined substantially as set forth.

8. A punching and shearing machine comprising in its mechanism, a first gate, means for moving the gate, a second gate carried by the first gate and adapted to be moved 50 therewith, and a gag coöperating with the gates and adapted to cause the second gate to remain stationary while the first gate is in motion, combined substantially as set forth.

55. 9. A punching and shearing machine comprising in its mechanism, a first gate, means for moving the gate, a second gate carried by the first gate and adapted to be moved therewith, a gag operating with the gates 60 and adapted to cause the second gate to remain stationary while the first gate is in motion, and manually controlled mechanism for moving the second gate relative to the first one prior to the adjustment of the gag 65 to position corresponding with conjoint

movement of the gates, combined substantially as set forth.

10. A punching and shearing machine comprising in its mechanism, a first gate, means for moving the gate, a second gate 70 carried by the first gate and adapted to be moved therewith, a gag operating with the gates and adapted to cause the second gate to remain stationary while the first gate is in motion, manually controlled mechanism 75 for moving the second gate relative to the first one prior to the adjustment of the gag to position corresponding with conjoint movement of the gates, and counterbalancing mechanism connected to the second gate 80 to serve in elevating that gate when gagged out of action, combined substantially as set forth.

11. A punching and shearing machine comprising in its mechanism, a first gate, 85 means for moving the gate, a second gate carried by the first gate and adapted to be moved therewith, a gag operating with the gates and adapted to cause the second gate to remain stationary while the first gate is in 90 motion, manually controlled mechanism for moving the second gate relative to the first one prior to the adjustment of the gag to position corresponding with conjoint movement of the gates, counterbalancing mechanism 95 connected to the second gate to serve in elevating that gate when gagged out of action, and a stop to limit the elevation of the second gate, combined substantially as set forth.

100. 12. A punching and shearing machine comprising in its mechanism, a pair of gates each carrying a tool, mechanism for actuating the gates, a gag coöperating with the first gate of the pair and the tool carried by 105 that gate, mechanism for causing the second gate to be moved by the first gate, a gag coöperating with both gates, a handle for adjusting the first gag, a handle for adjusting the second gag, a projection carried by one 110 of the gates, a lug operatively connected with one of the handles and engaging said projection, and operative connections between the other handle and said lug and adapted to prevent both gags being put to 115 ungagging position at the same time, combined substantially as set forth.

120. 13. A punching and shearing machine comprising in its mechanism, a frame, a die carried by the frame, a lower shear-blade carried by the frame at the level of the top of the die, a punch-gate, a punch carried by the punch-gate, a punch-gag coöperating between the punch and punch-gate, a shear-gate carrying the upper shear-blade and movable relative to the punch-gate, counterbalancing mechanism for normally holding the shear-gate in upward open position, a stop to limit the upward motion of the shear-gate, manually operated means for depress- 125 130

ing the shear-gate relative to the punch-gate, and means for connecting the two gates after the shear-gate has been moved downwardly relative to the punch-gate so that the gates 5 may move in unison, combined substantially as set forth.

14. A punching and shearing machine comprising in its mechanism, a punch-gate, a punch carried thereby, a gag coöperating 10 with the punch and punch-gate, a shear-gate adapted to be moved by the punch-gate, a shear-gag-block coöperating with the two gates and carried by the punch-gate, a shear-gag handle carried by the punch-gate, and 15 operative connections from said handle to the shear-gag-block, combined substantially as set forth.

15. A punching and shearing machine comprising in its mechanism, a frame having side housings, a punch-gate having its 20

ends guided in said housings, a bridgetree disposed at the rear of the punch-gate and connecting the two housings, a shear-gate disposed between the punch-gate and the bridgetree, and guiding devices connecting 25 the shear-gate and bridgetree, combined substantially as set forth.

16. A punching and shearing machine comprising in its mechanism, two gates, a tool carried by each gate, a gag coöperating 30 with one of the gates and the tool carried by it, and a gag adapted to be moved into such position as will connect the two gates and cause them to move in unison, combined substantially as set forth.
